United States Patent

Des. 239,369
Patented Mar. 30, 1976

239,369

PACKAGING CONTAINER

Marcus Bressler, 505 Smithfield Ave.,
Winnipeg, Manitoba, Canada

Filed Nov. 13, 1973, Ser. No. 415,344

Claims priority, application Canada Oct. 23, 1973

Term of patent 14 years

Int. Cl. D9—01

U.S. Cl. D9—164

FIG. 1 is a side elevational view of a packaging container embodying my new design;

FIG. 2 is a front elevational view;

FIG. 3 is a bottom plan view; and

FIG. 4 is a top plan view thereof.

The side opposite that seen in FIG. 1 is a mirror image of the side shown.

I claim:

The ornamental design for a packaging container, as shown and described.
